UNITED STATES PATENT OFFICE.

HARRY TEEGAN, OF DES MOINES, IOWA.

AUXILIARY AIR-INTAKE MECHANISM.

Application filed May 23, 1921. Serial No. 471,828.

To all whom it may concern:

Be it known that I, HARRY TEEGAN, a citizen of the United States of America, and resident of Des Moines, Polk County, Iowa, have invented a new and useful Auxiliary Air-Intake Mechanism, of which the following is a specification.

The object of this invention is to provide an improved device or mechanism by means of which an auxiliary supply of atmospheric air may be injected into and within the fuel mixture immediately prior to its entrance to the cylinders of an internal combustion engine.

15 A further object of this invention is to provide improved means for delivering atmospheric air to and distributing it evenly and uniformly relative to the fuel mixture in the form of a jet or spray.

20 A further object of this invention is to provide an improved auxiliary air mechanism capable of being used also as a priming device for starting an internal combustion engine.

25 A further object of this invention is to provide an improved auxiliary air inlet mechanism capable of being used to introduce to the cylinders of an internal combustion engine a fluid such as a priming or a cleaning medium.

30 A further object of this invention is to provide a device of the character described equipped with an improved valve mechanism under manual control.

35 With these and other objects in view my invention consists in the construction, arrangement and combination of elements hereinafter set forth, pointed out in my claims and illustrated by the accompanying drawing, in which—

Figure 1 is a side elevation illustrating a portion of an internal combustion engine equipped with my improved mechanism. Figure 2 is a side elevation of the distributing member, partly in section centrally and longitudinally thereof. Figure 3 is a cross-section on the line 3—3 of Figure 2 and showing the supply pipe connected with the distributing member. Figure 4 is a face view of the valve chamber with the valve plate removed. Figure 5 is an inner face view of the valve plate detached. Figure 6 is a face view of the valve chamber and plate assembled, dotted lines indicating various positions of the groove of the valve plate with respect to the ports of the cham-

ber. Figures 2 to 6 inclusive are on a scale enlarged relative to Figure 1.

In the construction of the mechanism as shown the numeral 10 designates a distributing member which is relatively narrow and flat and is preferably of such general shape as to fit between and conform in outline to the flanges 11 and 12 of a carburetor 13 and intake manifold 14 of an internal combustion engine, which flanges usually are placed in contacting position and secured together by means of bolts 15 or machine screws; and said distributing member is formed near its ends with holes 16 to receive loosely said bolts or screws. The distributing member 10 is formed in its central portion with a circular hole 17 extending therethrough and adapted to register with the openings of the flanges 11, 12 and 70 form a continuation of the passage between the carburetor and manifold, through which fuel mixture passes on its way from the carburetor to the manifold and thence to the engine cylinders. The distributing 75 member 10 also is formed with an annular groove or channel 18 circumferentially of the central hole 17 and spaced from both side faces of said member. A lining 19 of annular form and relatively thin, is 80 mounted snugly in the central hole 17 of the distributing member and covers the annular groove or channel 18, said lining preferably extending entirely through said member and flush at its ends with the side walls 85 thereof. The lining 19 is formed with a central circumferential row of jet openings 20 of small diameter extending through it and forming a means of communication 90 from the groove or channel 18 to the central hole 17, and consequently to the path traversed by the fuel mixture. The distributing member 10 is formed near one end with an extension 21 projecting beyond its body outline and beyond the margins of 95 the flanges 11 and 12 between which it is confined, and said extension is formed with a tapped hole 22 extending therethrough. The distributing member 10 may be formed with bosses 23 on opposite sides of the extension 21 around the opposite ends of the tapped hole 22, whereby the length of said hole is increased relative to the thickness of the member and extension. A port or channel 24 is formed in the distributing 100 member 10 and the extension thereof and forms a means of communication between

the tapped hole 22 and the annular groove or channel 18.

- A valve chamber is provided and is formed of a base 25 and rim 26 extending in one direction therefrom and of circular form. The chamber also is formed with a peripheral flange 27 at its base adapted to contact with the surface of a dash 28 or instrument board of a vehicle on which the device is to be used, and secured in position by screws passing through holes 29 in said flange. The valve chamber is formed with a central hole 30 extending through its base 25 and with a plurality of ports extending through said base between said central hole and the rim 26, said ports in this instance being three in number and designated by the numerals 31, 32 and 33. A valve plate 34 is provided, of circular form and adapted to fit within the rim 26 of the chamber with its inner face in contact with the base 25, said plate preferably being formed with a peripheral flange 35 overlapping the outer margin of the rim 26 of the valve chamber. The valve plate 34 is formed with a central hole 36 and is pivoted for rotary oscillation on a screw or bolt 37 extending therethrough and through the central hole 30 of the chamber base 25, and secured by a nut 38. The valve plate 34 is formed on its inner face with an arcuate groove or channel 39, spanning approximately one-hundred eighty degrees, adapted to be so positioned as to provide means of communication between any selected two of the ports 31, 32, 33 of the chamber base 25. The valve plate 34 preferably is provided on its outer face with finger lugs 40 to facilitate manual operation thereof. One of the ports of the valve chamber base 25, in this instance 31, provides means for admitting atmospheric air to the valve chamber. This port preferably opens through the dash 28 of the vehicle, communicating with a pipe such as 41 projecting forwardly through said dash, so that air is admitted thereto from the engine hood rather than from the driver's compartment, to prevent annoyance to the occupants of the vehicle because of any hissing or unpleasant noises which might be produced by the entrance of air to the chamber. Another of the ports, such as 32, communicates with a supply pipe 42 extending forwardly through the dash 28 and connected by a union 43 or coupling to an elbow 44 threaded into the tapped hole 22 of the extension of the distributing member 10. A plug 45 is screwed into the opposite end of the tapped hole 22 and prevents escape of air from the distributing member except through the jet openings 20. The other of the ports of the valve chamber, in this instance 33, communicates with a passage or channel 46 formed radially in the base 25

and opening through the uppermost part of the rim 26.

As the inner face of the valve plate 34 contacts with the base 25 of the valve chamber, there is no communication between the various ports of said base except by means of the arcuate groove or channel 39 of said plate. When it is desired to introduce atmospheric air to the fuel mixture auxiliary to the common means, the valve plate 34 is turned to such position that the arcuate groove or channel 39 overlaps and forms a connection or communication between the ports 31 and 32, as indicated by dotted lines in the lower portion of Figure 6. When the valve plate is so arranged the suction action of the engine, when operating, causes air to be drawn into the valve chamber through the inlet pipe 41, through the groove or channel 39 to the port 32 and thence through the pipe 42 and elbow 44 to the hole 22 of the distributing member, whence it passes by the port or channel 24 to the annular groove or channel 18 and through the jet openings 20 of the lining 19 to the passage 17 through which the fuel mixture is moving from the carburetor to the engine cylinders; and the atmospheric air is thus directed from all sides, in a fine jet or spray, into and caused to mix intimately with the fuel mixture. Thus under certain conditions considerable saving of fuel may be accomplished and greater efficiency be obtained.

When no additional or auxiliary atmospheric air is desired in the fuel mixture the valve plate is so turned as to form communication between the ports 31 and 33, as indicated by dotted lines at the left of Figure 6, in which position the port 32 and air supply pipe 42 are closed by the smooth surface of the valve plate.

The mechanism may also be used for priming the engine to facilitate the operation of starting in cold weather, and for such use the valve plate 34 is so turned as to cause the arcuate groove 39 to overlap and form communication between the ports 33 and 32, as indicated by dotted lines at the right in Figure 6. Priming fluid, such as high test gasoline, ether or the like, may be introduced to the port or passage 46 as by means of a squirt can, and passes through said passage to the port 33, through the arcuate groove or channel 39 to the port 32 and thence to the engine cylinders as previously described with relation to the passage of atmospheric air.

At times it may be desirable to use the mechanism to assist in the operation of introducing a cleaning or carbon-removing liquid to the engine cylinders, in which event the valve plate is turned to the position first described, where it forms a communication between the ports 31 and 32.

The inner end of the inlet pipe 41 preferably is turned down as shown in Figure 1 so that it may be caused to enter the neck of a bottle or other container of the fluid 5 to be used, and the suction action of the running engine operates to withdraw the liquid from the container through the mechanism in the manner previously described with respect to the passage of atmospheric 10 air.

The distributing member may be mounted in any position to adapt it for use on any make of engine or motor vehicle, either horizontally or vertically and with the extension 21 projecting in either direction, as the elbow 44 may be mounted in either end of the tapped hole 22 and the plug 45 employed to close the opposite end.

Lugs 47, 47 may be located in spaced positions circumferentially of the valve plate 34, to guide the operator in properly positioning said plate, as by engagement with a pin 48 projecting beyond the rim 26 of the chamber.

25 I claim as my invention—

1. In a device of the class described, a

valve chamber formed with three ports, one of said ports being adapted to admit atmospheric air and the other to admit a liquid to said chamber, the third of said ports being 30 connected to an air supply pipe, and a rotary valve member formed with an arcuate channel adapted to form communicating means selectively between said third port and the other two.

2. In a device of the class described, a valve chamber formed of a base and a rim, said base having three ports therein, one of said ports being adapted to admit air and another a liquid to said chamber, the third 40 of said ports being connected to a supply pipe, a rotary valve member mounted within said rim and having a face contacting said base, said valve member being formed on its inner face with an arcuate groove adapted to form communicating means selectively between the third port and the other two.

Signed at Des Moines, in the county of Polk and State of Iowa, this 21st day of April, 1921.

HARRY TEEGAN.
